UNITED STATES PATENT OFFICE

2,260,553

PRESS FOR PRINTING SPOTS OF WAX
CARBON ON PAPERDonald L. Boyd, Huntington, W. Va., assignor to
Carb-O-Spot Corporation, Athens, Ohio

Application March 6, 1940, Serial No. 322,456

7 Claims. (Cl. 101—122)

My invention relates to that class of presses which are designed to print spots of wax carbon on different areas of paper. A press of this type is described in United States Letters Patent to Rutkoskie, Reissue No. 19,642. That press however is a reciprocating type bed press of the Kelly type adapted to handle wax carbon.

A Kelly press however will not handle large quantities economically. As a consequence, it is very desirable to produce a rotary press capable of producing these kinds of wax carbon forms. Such presses have, however, been regarded as too expensive to justify their construction.

My invention has for its principal object to equip a press of this type with means whereby wax carbon can be applied to paper in spots of predetermined size and shape.

It may if desired be used as an attachment or built in as part of a carbon paper machine such as now used by carbon paper manufacturers. These machines apply carbon directly to the paper from rollers revolving against the surface of the paper, the paper being fed from a roll and rewound after the carbon has been applied.

By the use of my invention I provide an endless stencil having cut-away portions of the predetermined size and shape for the desired spots and then running the stencil between the paper which is to be printed and the ink fountain or feeding roller at the time the paper contacts with this roller. Obviously, the uncut portion of the stencil will prevent contact of the inking roller or rollers with the paper while the cut-out portions of the stencil will permit the rollers carrying wax carbon to print on the paper the desired spots.

As described in the Rutkoskie and other patents of similar character, wax carbon is very difficult to handle and must be handled at a critical temperature and the parts of the press that come in contact with it must be heated to the proper degree.

A further object of my invention is to provide an improved stencil for this purpose.

A further object is to provide an improved method of cutting the stencil.

A further object is to provide means for controlling the movement of the stencil so as to insure proper registering.

My means of accomplishing the foregoing objects may be more readily understood by having reference to the accompanying drawing, in which:

Fig. 1 is a perspective view of my improved press;

Fig. 2 is a fragmentary detail view showing the drive for the stencil belt;

Fig. 3 is a fragmentary detail view showing method of tightening the drive for stencil belt; and

Fig. 4 shows the means for manufacturing the stencil belt.

Similar reference numerals refer to similar parts throughout the entire specification.

In the drawing, I have illustrated only those parts of the press which are necessary to explain the operation of my invention. The omitted parts being standard and so well understood in the industry as to render specific detailed description of the same unnecessary.

As shown, the press consists of two side frames formed by uprights 1, 2, 3 and 4, the uprights 1 and 2 being connected together by a base 5 while the uprights 3 and 4 are connected together by a base 6. They are also connected at the top by top bars 7.

In the uprights 2 and 4 I mount a shaft 8 which carries the paper roll 9. The paper is carried from this roll around a cylinder 10 which is carried by a shaft 11 journaled in the upright members 1 and 3 of the frame. This cylinder is provided with means for heating the same (not shown). This can be done by suitable electric heating elements, or it may be done with a hot fluid, as desired. This cylinder is in contact with the ink fountain or transfer roll 12 which dips into the ink fountain 13.

The paper passes over the cylinder 10 and preferably over a cylinder 14 carried by a shaft 15 journaled in the side frames. This cylinder is preferably for the purpose of chilling the wax carbon and is preferably provided with means for circulating ice water therethrough or any other standard form for chilling the cylinder 14 may be employed.

The paper is then carried up to a rewind cylinder 16 upon which it is wound in the usual manner, this cylinder being mounted upon shaft 17 journaled in the uprights 2 and 4.

The stencil 18 consists of an endless belt which is preferably formed of ordinary stencil paper which is preferably laminated with a moisture proof material. I have found that Cellophane serves very satisfactorily for this purpose. Cut-out portions 19 are formed in the stencil 18 of the particular size desired. As will be clear from the drawings, the stencil 18 passes between the ink fountain or distributing roller 12 and the heated cylinder 10.

The shaft 8 which carries the paper roll 9

is provided with a gear 20 which meshes with an intermediate gear 21 which in turn meshes with a gear 22 mounted upon a shaft 23 suitably journaled in the side frame of the press. This shaft 23 carries a pair of wheels 24 provided with teeth 24' clearly seen in the detail view, Fig. 2, which teeth are fitted to and coincide with perforations or notches 25 formed in each edge of the stencil. A similar set of gearing and toothed wheels, are provided on a shaft 25' mounted at the upper part of the frame. An idler shaft 26 is provided at the forward part of the press and is provided with a pair of wheels formed with teeth 24' to engage the perforations or notches 25 in the stencil. This shaft 26 however is an idler and is slidably mounted in slots 27 cut in the top bars 7 of the frame and is held in place by means of a nut 28 thus providing for an adjustment of the stencil 18. A graduated scale 29 is provided so as to set the shaft 26 for any desired size of stencil.

The operation of the device is as follows: the press is driven in any standard way (not shown). This drive draws the paper from the roll 8 over the cylinder 10, as it passes intermediate the ink fountain roller 12, that roller will deposit the wax carbon from the heated ink fountain 13 on the area of the paper exposed by the cut-away portions 19 of the stencil. As the paper travels toward the rewind cylinder 16 it passes over the cold or chilling cylinder 14, if one is employed, after which it may be brushed or burnished in any of the standard ways in the manufacture of carbon paper before it reaches the rewinding cylinder 16 upon which it is wound. As explained, it is essential that the ink fountain 13, the ink fountain roller 12, and the cylinder 10 must be heated to the critical temperature at which wax carbon can be suitably worked. The cold cylinder 14 may or may not be employed as desired. In some instances, it has been found desirable to omit it.

It will be obvious that although I have shown a specific shape for cut-away portions on the stencil, that these can be of any size and shape desired. I merely use this type of cut-away portion because it is the one which I have been accustomed to print on tax tickets. It will also be clear from the foregoing description that the stencil is controlled so that it cannot shift either sideways or lengthwise, thus insuring proper registration at all times while provision of the train of gears to move the stencil in synchronization with the paper roll and rewind cylinder insures exact registration at all times.

Having described my invention, what I regard as new and desire by secure by Letters Patent is:

1. In a rotary press for printing wax carbon spots on a continuous paper web, having a frame, a driven shaft on which is mounted a roll of paper, a heated ink fountain, a heated ink fountain roller which contacts a heated cylinder over which the web of paper passes, a rewinding roll carried by a shaft, and a chilling cylinder between the heated cylinder and the rewinding roll; an endless stencil having cut-out portions of desired area, said stencil passing intermediate the ink fountain roller and the heated cylinder, and means to positively control the said stencil.

2. In a rotary press for printing wax carbon spots on a continuous paper web, having a frame, a driven shaft on which is mounted a roll of paper, a heated ink fountain, an ink fountain roller, which contacts a heated cylinder over which the web of paper passes, and a rewinding

70 roll carried by a shaft; an endless stencil having cut-out portions of desired area, said stencil passing intermediate the ink fountain roller and the heated cylinder, and means to positively control the said stencil.

3. In a rotary press for printing wax carbon spots on a continuous paper web, having a frame, a driven shaft on which is mounted a roll of paper, a heated ink fountain, an ink fountain roller, which contacts a heated cylinder over which the web of paper passes, and a rewinding roll carried by a shaft; an endless stencil having cut-out portions of desired area, said stencil passing intermediate the ink fountain roller and the heated cylinder, said stencil having a plurality of perforations adjacent each edge, driven means which engage said perforations, said driven means being synchronized with travel of the paper.

20 4. In a rotary press for printing wax carbon spots on a continuous paper web, having a frame, a driven shaft on which is mounted a roll of paper, a heated ink fountain, an ink fountain roller which contacts a heated cylinder over which the web of paper passes, and a rewinding roll carried by a shaft; an endless stencil having cut-out portions of desired area, said stencil passing intermediate the ink fountain roller and the heated cylinder, said stencil having a plurality of perforations adjacent each edge, a gear on said driven shaft, an intermediate gear, a pair of notched wheels the teeth of which engage perforations in said stencil, a shaft on which said gears rotate, and a gear fixed on said shaft in mesh with the intermediate gear.

25 5. In a rotary press for printing wax carbon spots on a continuous paper web, having a frame, a driven shaft on which is mounted a roll of paper, a heated ink fountain, an ink fountain roller which contacts a heated cylinder over which the web of paper passes, and a rewinding roll carried by a shaft; an endless stencil having cut-out portions of desired area, said stencil passing intermediate the ink fountain roller and the heated cylinder, said stencil having a plurality of perforations adjacent each edge, a gear on said driven shaft, an intermediate gear, a pair of notched wheels the teeth of which engage perforations in said stencil, a shaft on which said gears rotate, and a gear fixed on said shaft in mesh with the intermediate gear.

30 6. In a rotary press for printing wax carbon spots on a continuous paper web, having a frame, a driven shaft on which is mounted a roll of paper, a heated ink fountain, an ink fountain roller which contacts a heated cylinder over which the web of paper passes, and a rewinding roll carried by a shaft; an endless stencil having cut-out portions of desired area, said stencil passing intermediate the ink fountain roller and the heated cylinder, and means to adjust said stencil.

35 7. In a rotary press for printing wax carbon spots on a continuous paper web, having a frame, a driven shaft on which is mounted a roll of paper, a heated ink fountain, an ink fountain roller which contacts a heated cylinder over which the web of paper passes, and a rewinding roll carried by a shaft; an endless stencil having cut-out portions of desired area, said stencil passing intermediate the ink fountain roller and the heated cylinder, means to adjust said stencil, said means comprising an idler shaft slidably mounted in slots in said frame, a pair of notched wheels on said shaft, a graduated scale on said frame adjacent said slot, and means to hold said idler shaft in position.

40 8. In a rotary press for printing wax carbon spots on a continuous paper web, having a frame, a driven shaft on which is mounted a roll of paper, a heated ink fountain, an ink fountain roller which contacts a heated cylinder over which the web of paper passes, and a rewinding roll carried by a shaft; a pair of shafts mounted in said frame adjacent the paper and rewinding roll, a pair of notched wheels fixedly secured to each shaft, a gear adjacent one end of each shaft, intermediate gears in mesh therewith, and driven gears on the shaft of said rolls which mesh with the intermediate gears.

DONALD L. BOYD.
